METHOD OF AND MACHINE FOR APPLYING TAPE

Filed Jan. 15, 1926

Patented Sept. 2, 1930

1,775,070

UNITED STATES PATENT OFFICE

FREDERICK M. FURBER, DECEASED, LATE OF REVERE, MASSACHUSETTS, BY SAMUEL R. CUTLER, ADMINISTRATOR, OF REVERE, MASSACHUSETTS, ASSIGNOR TO UNITED SHOE MACHINERY CORPORATION, OF PATERSON, NEW JERSEY, A CORPORATION OF NEW JERSEY

METHOD OF AND MACHINE FOR APPLYING TAPE

Application filed January 15, 1926. Serial No. 81,428.

This invention relates to methods of and machines for applying strips to pieces of sheet material and is herein illustrated as embodied in a machine for applying tape to parts of 5 the uppers of boots and shoes.

In the manufacture of boots and shoes it is common practice to apply tape to shoe uppers or parts thereof usually for the purpose of reinforcing the edges or margins of quarters, vamps, etc., and sometimes not only to reinforce the shoe part but to prevent the lining from showing through perforations in the shoe part. In the latter case a colored tape is used and is applied over the perforations on the inside of the shoe part.

The tape is ordinarily supplied from a reel, the free end applied progressively to a shoe part until the desired length has been laid in place and the tape then severed preparatory 20 to applying tape from the reel to the succeeding shoe part. Hitherto considerable difficulty has been experienced in performing this severing operation by reason of the fact that the tape, at the locality in which it must be 25 severed, is slack so that the cutting-off knife either does not make a clean cut or fails to sever the tape completely.

According to one feature of the present invention, the tape is pulled taut just prior to 30 the severing operation and maintained taut while this operation is performed. In the illustrated machine, the tape is drawn from a reel by a combined tape applying and feeding member, the tape on its way from the reel 35 to the applying and feeding member passing through a guide member which engages the tape frictionally; and, at the end of the applying operation when it is desired to sever the tape, this guide member is moved away 40 from the tape applying member so as to pull the tape taut between these two members preparatory to severing the tape. The tape may then be easily and cleanly cut.

According to another feature of the invention, cutting means is provided which is arranged to become operative after the tape has 45 been pulled taut. In the illustrated machine, the guide member and the cutter are operated in timed relation by an operator-controlled member manipulation of which just prior to

the end of a tape laying operation causes the following operations to take place in sequence. The guide is moved away from the tape applying member to pull the tape taut; the cutter moves across the tape to sever it 55 while taut and then moves back into inoperative position; the guide moves toward the tape applying member so as to present the free end of the severed tape to that member preparatory to the application of tape to a succeeding shoe part.

According to another feature of the invention, the work—the shoe part and the tape—is fed and the tape applied continuously. In the illustrated machine there is provided for 65 this purpose a small driven roller which may be heated if desired in order to soften the thermoplastic cement with which one side of the tape is commonly coated. With this construction the machine operates rapidly and 70 permits the tape to be laid in curved patterns since it is held down only in a locality of small area.

These and other features of the invention, including certain details of construction and 75 combinations of parts, will be described as embodied in an illustrative machine and pointed out in the appended claims.

Referring now to the accompanying drawings:—

Figure 1 is an end elevation partly in section of a machine in which the present invention is embodied, a piece of sheet material being shown in process of having a strip applied to it;

Figure 2 is a perspective of the work-engaging parts of the machine in the same position which they occupy in Figure 1;

Figure 3 is a detail principally in elevation showing the work-engaging parts in a 90 different position, and

Figure 4 is an elevation showing more particularly the operative and inoperative positions of the cutter.

The machine comprises a base 5 having a 95 standard 7 extending upwardly and rearwardly therefrom, said standard carrying a driving shaft 9 which may be rotated from any suitable source of power. This shaft passes through a casing 11 which is rigid 100

with the standard; and, in this casing, is mounted a train of gears which connect the rotary shaft 9 with the tape-applying and work-feeding roller 13. This train of gears 5 comprises a small gear 15 fast to the shaft 9 and a series of idly mounted intermeshing gears 16, 17, 18, 19, 20, 21, 22, 23 and 24, the last-named gear being fast to the small applying and feeding roller 13 which itself may 10 be corrugated or toothed to facilitate its work-feeding action. Rotatably mounted in the base 5 is a comparatively large roller 25, said roller being idly mounted and serving to support the work at the locality in which 15 it is engaged by the applying roller 13, which is rotated continuously during the operation of the machine.

In the operation of the machine, the sheet material 100, hereinafter referred to as a shoe 20 part, and the strip 200, hereinafter referred to as tape, are presented between the driven roller 13 and the idle roller 25 and fed through the machine until near the completion of the tape-laying operation, when the 25 tape is severed by the swinging rotary cutter 27, as indicated in Figure 3, a short distance in advance of the applying tool or roller 13, the trailing end of the partly applied piece of tape being applied to the shoe part 100 30 after the severing operation. It should be particularly noted that the lower end of the casing 11 in which the applying roller 13 is mounted extends rearwardly as well as upwardly and that the shape and inclination of 35 this casing permits the operator to observe the operation of the roller and the manner in which the tape is being laid. The roller 13 may be heated, if desired, by an electric heating unit 29 mounted in an extension of 40 the casing.

The tape 200 is carried by a reel 31 which is supported upon a post 33 bolted to the top of the standard 7. Extending horizontally from the standard is a bracket 35; and, pivoted to this bracket at 37 is a tape guide or 45 presenter 39. This tape presenter has the outer face at its lower end rounded, as shown in Figures 1 and 3, and has fastened to its lower end a three-sided metal piece 41 to 50 provide a guide slot for the tape. Mounted upon the presenter or guide 39 is a friction tension device for the tape comprising a plurality of spaced pins 43, 44, these pins being in two sets. The set of three pins numbered 55 43 is carried by a block 45 integral with a plate 46 which is riveted to the presenter 39. The set of two pins numbered 44 is carried by a block 48 integral with slides 47 which lie in guideways formed in the block 45. A 60 thumb-screw 49, rotatably mounted in the block 45 but held from longitudinal movement with respect thereto, is threaded through the block 48 so that by turning the screw the block 48 may be adjusted with respect to the block 45. The free end of the

tape 200 is led from the reel 31 over the bracket 35, in and out between the pins 43, 44 and through the guide slot at the lower end of the presenter, the degree of friction with which the tape is held by the presenter depending upon the adjustment of the thumb-screw 49. After the desired length of tape has been laid upon the shoe part, the presenter 39 is swung to the right about the pivot 37, as shown in Fig. 3, to pull the tape 70 taut and maintain it taut while the tape is severed. The presenter normally occupies the angular position shown in Figure 1, relatively close to the applying roller 13, being held in that position by means presently to be described, against the tension of a spring 51 connected at one end to a stationary part of the machine and at the other end to a stud 53 which is carried by an upright extension of the presenter. On the stud is mounted a 85 roll 55 which is held by the spring in contact with a cam 95 on the end of an arm 57 carried by a hub 59 said hub being fast to a rock-shaft 61 mounted in bearings in the standard 7. Fast to this rock-shaft is one end of a lever 63 to the other end of which is pivoted the upper end of a treadle rod 65, the rod being normally held down by a spring (not shown) and being adapted to be moved up when a treadle (also not shown) is depressed. 90

The machine, as has been indicated above, is provided with a cutter for severing the tape, said cutter being shown as a rotary disk cutter 27 which is swung from inoperative to operative position, as shown in Figure 3, 100 when the presenter is swung to the right to pull the tape taut. This cutter is fast to a pulley 67 rotatably mounted at the lower end of an arm 69 the upper end of which is pivoted about a shaft 71 and has a right-angled extension 73 at the end of which is a beveled segmental rack 75 the teeth of which mesh with the teeth of a complementary rack 77 carried at the outer end of an arm 79 the inner end of which is integral with the same hub 59 with which the arm 57 is integral, so that the two arms are 110 swung in unison. The cutter pulley 67 is driven by a belt 81 which passes around said pulley and around a pulley 83 fast to the outer end of the shaft 71. The inner end of said shaft has fast to it a small gear 85 which meshes with a gear 87 fast to one end of a shaft 89 to the other end of which is fast a spiral gear 91, said last-named gear 120 meshing with a larger spiral gear 93 fast to the driving shaft 9. When the arms 57, 79 are in their up position as shown in Figures 1 and 2, the cutter 27 is in inoperative position, as best shown in Fig. 4, and the presenter 39 occupies its position nearest to the applying roller 13, being held in this position, as has been indicated, by a projecting cam 95 on the outer end of the arm 57. When 125 the treadle is manipulated to lower the arms 130

- 57, 79 to their down position, the presenter, under the influence of the spring 51, is immediately swung away from the applying roll 13, as shown in Figure 3, and the cutter is 5 swung across the tautly held tape, as shown in full lines in Figure 3, and in dotted lines in Figure 4, to sever the tape. It will be noted that this movement of the cutter takes place in a direction widthwise of the tape 10 and during the continuous feeding movement of the tape. After the tape has been severed, a succeeding shoe part is presented to the machine immediately behind the preceding shoe part and the arms 57, 79 are caused to swing 15 up again whereupon the cutter is swung to inoperative position and the presenter swung to the left to present the free end of the severed tape to the applying roller 13. It will be noted that the presenter 39 may be 20 held in its right-hand position for any desired interval after the tape has been severed and a succeeding shoe part fed to the machine so that the operator may start the laying of the free end of the tape at the leading 25 end of the shoe part or at any desired distance from said leading end. It should also be noted that the operator may sever the tape at any time after it has begun to be applied to the shoe part. It is thus possible to 30 apply tape of any desired length to any desired locality on the shoe part; and, inasmuch as the tape is applied to the shoe part from above, the operator may observe its application and thus judge accurately just 35 when to sever the tape so that its trailing edge may be laid flush with the trailing edge of the shoe part or spaced a given distance from said trailing edge of said shoe part as may be desired.
- 40 In order to facilitate the guiding of the shoe part, an edge gage 97 of any suitable type may be adjustably fastened to the table 98 of the machine as by a clamping screw 99 which passes through a slot in the gage and is threaded into the table.
- 45 Having thus described my invention, what I claim as new and desire to secure by Letters Patent of the United States is:—
1. A machine of the class described having, 50 in combination, a support for a piece of sheet material to which a reinforcing strip is to be applied, means for applying the strip to the material, and operator-controlled means for pulling the strip taut in a locality adjacent to that engaged by the applying means preparatory to severing the strip.
2. A machine of the class described having, 55 in combination, a support for a piece of sheet material to which a reinforcing strip is to be applied, means for applying the strip to the material, means for heating the applying means, and operator-controlled means for pulling the strip taut in a locality adjacent to that engaged by the applying means preparatory to severing the strip.
3. A machine of the class described having, 60 in combination, a support for a piece of sheet material to which a reinforcing strip is to be applied, means for applying the strip to the material, means for severing the strip at a locality in advance of that engaged by the applying means, and means for pulling the strip taut in that locality prior to the severing operation. 70
4. A machine of the class described having, 75 in combination, a support for a piece of sheet material to which a reinforcing strip is to be applied, means for applying the strip to the material, means for guiding the strip to the material as it is applied, means for severing the strip, and means for pulling the strip taut prior to the action of the severing means. 80
5. A machine of the class described having, 85 in combination, a support for a piece of sheet material to which a reinforcing strip is to be applied, means for applying the strip to the material, means for guiding the strip to the material as it is applied, means for severing the strip in the locality between the applying means and the guiding means, and means for exerting a pull upon the strip in that locality to maintain it taut during the severing operation. 90
6. A machine of the class described having, 95 in combination, a support for a piece of sheet material to which a reinforcing strip is to be applied having, in combination, a member for applying the strip to the material, a strip presenter located in advance of the applier, a strip cutter arranged to operate in the locality between the presenter and the applier, and means for causing relative movement of separation between the presenter and the applier to pull the strip taut and maintain it taut during the operation of the cutter. 100
7. A machine of the class described having, 105 in combination, a support for a piece of sheet material to which a reinforcing strip is to be applied, means for applying the strip to the material and for feeding the strip and the material over the support, a strip presenter located in front of the applying means, said presenter having means for guiding the strip and for holding it frictionally, and means for moving the presenter toward the applying means to present the free end of the strip to said means and to guide the strip during its application to the material, and for thereafter moving the presenter away from the applying means so as to pull taut that portion of the strip lying between the applying means and the presenter preparatory to severing the strip. 110
8. A machine of the class described having, 115 in combination, a support for a piece of sheet material to which a reinforcing strip is to be applied, means for applying the strip progressively to the material, a strip presenter arranged to engage the strip at a locality in advance of that engaged by the applying 120
- means and the presenter preparatory to severing the strip. 125
- 130

means, a cutter for severing the strip between the applying means and the presenter, said cutter being movable at will from inoperative to operative position, and means for moving the presenter to cause the strip to be pulled taut when the cutter is moved to operative position.

9. A machine of the class described having, in combination, a support for a piece of sheet material to which a reinforcing strip is to be applied, a roller for applying the strip progressively to the material, a strip presenter arranged to engage the strip at a locality in advance of that engaged by the roller, a cutter for severing the strip between the roller and the presenter, said cutter being movable at will from inoperative to operative position, and means for moving the presenter to cause the strip to be pulled taut when the cutter is moved to operative position.

10. A machine of the class described having, in combination, a support for a piece of sheet material to which a reinforcing strip is to be applied, means for applying the strip progressively to the material, means for guiding the strip to the material as it is applied, a cutter for severing the strip, and means for pulling the strip taut prior to the severing operation and for thereafter presenting the free end of the severed strip to the applying means.

11. A machine of the class described having, in combination, a support for a piece of sheet material to which a reinforcing strip is to be applied, means for applying the strip progressively to the material, means for guiding the strip to the material as it is applied, a cutter for severing the strip, and a member manipulation of which operates the guide and the cutter alternately first to pull the strip taut, then to sever the strip and then to present the free end of the severed strip to the applying means.

12. A machine of the class described having, in combination, a support for a piece of sheet material to which a reinforcing strip is to be applied, means for applying the strip progressively to the material, a cutter for severing the strip, said cutter being normally in inoperative position, a strip presenter normally in a position close to the applying means but movable away from said means, and operator-controlled means for first moving the presenter away from the applying means to pull the strip taut and for moving the cutter to operative position to sever the strip and for thereafter moving the cutter to inoperative position and the presenter toward the applying means to present the free end of the severed strip to said means.

13. A machine of the class described having, in combination, a support for a piece of sheet material to which a reinforcing strip is to be applied, a member for applying the strip to the material, a guide for directing the

tape to the applying member, said guide being mounted for swinging movement toward and from said applying member, and a cutter mounted for swinging movement in a path the plane of which is at right angles to that of the guide.

14. A machine of the class described having, in combination, a support for a piece of sheet material to which a reinforcing strip is to be applied, means for feeding the material and the strip continuously over the support and for applying the strip to the material, means for guiding the strip to the material as it is applied, means for severing the strip, and means for pulling the strip taut prior to the action of the severing means.

15. A machine of the class described having, in combination, a support for a piece of sheet material to which a reinforcing strip is to be applied, means for applying the strip to the material, means for guiding the strip to the material as it is applied, means for severing the strip by a draw cut, and means for pulling the strip taut prior to the severing operation.

16. A machine of the class described having, in combination, a support for a piece of sheet material to which a reinforcing strip is to be applied, means for applying the strip to the material and for feeding the strip to the material, means for guiding the strip to the applying means, and a rotary cutter for severing the strip in advance of its point of application to the piece of sheet material.

17. A machine of the class described having, in combination, a support for a piece of sheet material to which a reinforcing strip is to be applied, means for applying the strip to the material and for feeding the strip and the material, means for guiding the strip to the applying means, a rotary cutter mounted for movement into the path of the strip for severing the strip, and means for moving said cutter from severing position in said path to inoperative position out of said path.

18. A machine of the class described having, in combination, a support for a piece of sheet material to which a reinforcing strip is to be applied, means for applying the strip to the material and for feeding the strip and the material, means for guiding the strip to the applying means, a rotary cutter mounted for movement into the path of the strip for severing the strip, and operator-controlled means for moving said cutter from severing position in said path to inoperative position out of said path.

19. A machine of the class described having, in combination, a support for a piece of sheet material to which a reinforcing strip is to be applied, means for applying the strip to the material and for feeding the strip and the material, means for guiding the strip to the applying means, and a rotary cutter for

- severing the strip, said cutter being mounted for movement across the strip.
20. A machine of the class described having, in combination, a support for a piece of sheet material to which a reinforcing strip is to be applied, means for applying the strip to the material and for feeding the strip and the material, means for guiding the strip to the applying means, a rotary cutter for severing the strip, said cutter being pivotally mounted, and operator-controlled means for swinging said cutter into engagement with the strip.
21. A machine of the class described having, in combination, a support for a piece of sheet material to which a reinforcing strip is to be applied, means for feeding the material and the strip continuously over the support and for applying the strip to the material, means for severing the strip at a locality in advance of that at which it is engaged by the applying means, and means for thereafter presenting the free end of the severed strip to the applying means.
22. A machine of the class described having, in combination, a support for a piece of sheet material to which a reinforcing strip is to be applied, a rotating member for feeding the material and the strip continuously over the support and for applying the strip to the material, means for severing the strip at a locality in advance of that at which it is engaged by the rotating member, and means for thereafter presenting the free end of the severed strip to the rotating member.
23. A machine of the class described having, in combination, a support for a piece of sheet material to which a reinforcing strip is to be applied, a rotary tool for applying the strip progressively to the material and for feeding the strip and the material, means for guiding the strip to the rotary tool, and a cutter operable to sever the strip between the rotary tool and the guiding means.
24. A machine of the class described having, in combination, a roller of comparatively large diameter for supporting a piece of sheet material to which a reinforcing strip is to be applied, a roller of small diameter for applying the strip progressively to the material and for feeding the strip and the material, means for guiding the strip to the feeding and applying roller, and a cutter operable to sever the strip between the applying roller and the guiding means.
25. A machine of the class described having, in combination, a support for a piece of sheet material to which a reinforcing strip is to be applied, an applying tool, means for operating said tool, and a casing at the lower end of which said tool is carried, said casing extending upwardly from the support and being inclined rearwardly of the machine.
26. A machine of the class described hav-
- ing, in combination, a support for a piece of sheet material to which a reinforcing strip is to be applied, an applying tool, means for operating said tool, a casing at the lower end of which said tool is carried, said casing extending upwardly from the support and being inclined rearwardly of the machine, and means for guiding the strip to the applying tool.
27. A machine of the class described having, in combination, a support for a piece of sheet material to which a reinforcing strip is to be applied, an applying tool, means for operating said tool, a casing at the lower end of which said tool is carried, said casing extending upwardly from the support and being inclined rearwardly of the machine, means for guiding the strip to the applying tool, and a cutter operating between the applying tool and the guide.
28. A machine of the class described having, in combination, a support for a piece of sheet material, means for guiding a piece of tape to said material, a driven roll for feeding both the material and the tape and for applying the tape to the material, and operator-controlled means for severing the tape.
29. The method of attaching a reinforcing strip to a piece of sheet material and severing the strip which comprises attaching the strip progressively to the material, pulling the strip taut at a selected stage in the attaching operation and severing the strip at a locality in which it is taut.
30. A machine for applying adhesive tape to a piece of sheet material, having in combination, means for applying the tape to the material and for feeding the material and the tape, a tape presenter normally positioned relatively close to said applying means and adapted to engage the tape in advance of the applying means, a tape cutter adapted to sever the tape in a locality between the applying means and the presenter, and operator-controlled means for moving the presenter away from the applying means near the end of the tape-laying operation and for causing the cutter to sever the tape.
31. A machine for applying an adhesive tape to a piece of sheet material, having in combination, a support for the sheet material, a tape applier, a tape presenter, a cutter, and operator-controlled means for moving the presenter away from the applier and simultaneously for moving the cutter to sever the tape.
32. A machine for applying an adhesive tape to a piece of sheet material, having in combination, a roll for supporting the work, a second roll for applying the tape to the material and for feeding the work, means for severing the tape, a tape presenter, and means for operating the presenter to present the severed end of the main portion of the

tape in position to be applied to a succeeding piece of sheet material.

33. A machine for applying an adhesive tape to a piece of sheet material, having in combination, a roll for supporting the work, a second roll for applying the tape to the material and for feeding the work, means for severing the tape, a pivoted tape presenter, and means for swinging the presenter about its pivot to present the severed end of the main portion of the tape in position to be applied to a succeeding piece of sheet material.

34. A machine of the class described having, in combination, means for applying adhesive tape to a piece of sheet material, and a cutting tool mounted for swinging movement across the path of the tape to be applied by said applying means, said tool being constructed and arranged to sever the tape by said swinging movement.

35. A machine of the class described having, in combination, means for progressively applying adhesive tape to a piece of sheet material, and a cutting tool mounted for lateral cutting movement widthwise of the tape from side to side and across the path of the tape in its passage to said applying means, said tool being constructed and arranged to sever the tape by said widthwise movement.

36. A machine of the class described having, in combination, means for applying adhesive tape to a piece of sheet material, a rotary disk cutter, a pivotally supported arm for carrying said cutter across the path of the tape to be applied by said applying means to sever the tape, and means for rotating said cutter.

In testimony whereof I have signed my name to this specification.

SAMUEL R. CUTLER,
*Administrator of the Estate of Frederick M.
Furber, Deceased.*

DISCLAIMER

1,775,070.—*Frederick M. Furber*, deceased, late of Revere, Mass., by Samuel R. Cutler, Revere, Mass., administrator. **METHOD OF AND MACHINE FOR APPLYING TAPE.** Patent dated September 2, 1930. Disclaimer filed by the assignee, *United Shoe Machinery Corporation*.

Hereby enters this disclaimer to said claims 13, 30, and 31 of said patent which are in the following words, to wit:

“13. A machine of the class described having, in combination, a support for a piece of sheet material to which a reinforcing strip is to be applied, a member for applying the strip to the material, a guide for directing the tape to the applying member, said guide being mounted for swinging movement toward and from said applying member, and a cutter mounted for swinging movement in a path the plane of which is at right angles to that of the guide.”

“30. A machine for applying adhesive tape to a piece of sheet material, having in combination, means for applying the tape to the material and for feeding the material and the tape, a tape presenter normally positioned relatively close to said applying means and adapted to engage the tape in advance of the applying means, a tape cutter adapted to sever the tape in a locality between the applying means and the presenter, and operator-controlled means for moving the presenter away from the applying means near the end of the tape-laying operation and for causing the cutter to sever the tape.”

“31. A machine for applying an adhesive tape to a piece of sheet material, having in combination, a support for the sheet material, a tape applier, a tape presenter, a cutter, and operator-controlled means for moving the presenter away from the applier and simultaneously for moving the cutter to sever the tape.”
